(57) **CLAIM**

The ornamental design for a drain, as shown and described.

DESCRIPTION

FIG. 1 is a top plan view of the drain;

FIG. 2 is a perspective view of the drain shown in FIG. 1; FIG. 3 is a cross-sectional view of the drain taken along line 3-3 in FIG. 2;

FIG. 4 is a cross-sectional view of the drain taken along line 4-4 in FIG. 2;

FIG. 5 is a cross-sectional view of the drain taken along line 5-5 in FIG. 2;

FIG. 6 is a front elevation view of the drain shown in FIG. 1;

FIG. 7 is a cross-sectional view of the drain taken along line 7-7 in FIG. 2;

FIG. 8 is a top plan view of a second variant of the drain; FIG. 9 is a front elevation view of the second variant of the drain shown in FIG. 8;

FIG. 10 is a cross-sectional view of the second variant of the drain taken along line 10-10 in FIG. 8;

FIG. 11 is a cross-sectional view of the second variant of the drain taken along line 11-11 in FIG. 8;

FIG. 12 is a cross-sectional view of the second variant of the drain taken along line 12-12 in FIG. 8;

FIG. 13 is a cross-sectional view of the second variant of the drain taken along line 13-13 in FIG. 8; and,

FIGS. 14 and 15 are detailed views along the Sections "14"

and "15," respectively, in FIG. 10.

The design consists of the visual features of the portions of the drain shown in solid lines in the drawings, whether those features are features of one of shape, configuration, ornament or pattern or a combination of any of these features. The portions shown in stippled lines are for illustrative purposes only and form no part of the claimed design. The bold, wavy lines do not constitute a feature of the design, and are included for illustrative purposes only in order to define the boundary of the design. The zig-zag lines illustrate an indefinite length of the design, and are included for illustrative purposes only.
